(57) **CLAIM**

The ornamental design for a heart rate monitor armband, as shown and described.

DESCRIPTION

FIG. 1 is a top perspective view of the heart rate monitor armband showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a partial enlarged view of portion 9 in FIG. 2. The dash-dot-dash broken lines define the bounds of the enlargement and form no part of the claimed design.

The broken lines depict portions in the drawings of the heart rate monitor armband that form no part of the claimed design.

1 Claim, 9 Drawing Sheets
